UNITED STATES PATENT OFFICE.

FRANK S. WICHMAN, OF CHICAGO, ILLINOIS, ASSIGNOR TO LOCOMOTIVE TERMINAL IMPROVEMENT COMPANY, OF CHICAGO, ILLINOIS, A CORPORATION OF MAINE.

BOILER-WASHING SYSTEM.

Application filed September 12, 1919. Serial No. 323,445.

This invention relates to a system of apparatus for use in washing out boilers, such, for instance, as boilers of steam locomotives, according to which the water and steam blown off from a boiler, in advance of the steps of washing out the boiler, and refilling it with clean warm water are, for the sake of economy, collected and separated into clean water, wash water, and sediment. 5

10 Among the objects of the present invention are to increase the proportion of the blown off water, which is vaporized and condensed and added to the clean water in the refilling tank of such a system; to eliminate the vibration and noise incident to the method heretofore followed of discharging the steam directly into the filling tank; to decrease the time of blowing off, and to provide a condenser in a boiler washing system, of the multiple unit type, which will 15 economically condense volatiles of a minor volume entering the condenser more or less constantly, for instance, the exhaust from steam actuated elements of the apparatus, and which will automatically act with a larger condensing capacity, whenever an excessive volume of volatiles accumulates in the condenser, for instance, the volatiles resulting from the blowing-off of a boiler. 20

25 Accordingly, one feature of the invention consists in providing the system with a condenser embodying two condensing elements, namely, a first condensing element which is normally active and of sufficient capacity to condense a minor volume of volatiles delivered more or less constantly to the condenser and a second condensing element which is normally inactive and of a capacity which adapts it to condense a major volume 30 of volatiles accumulating in the condenser in excess of the capacity of the first condensing element, at irregular intervals; and thermostatic means adapted to actuate the second condensing element and so located 35 that it is subject to the heating effect of volatiles accumulating within the condenser in excess of the capacity of the first condensing element, the said condenser being preferably adapted to maintain, on the 40 vapor outlet of the separator, by efficient condensation, a negative pressure or partial vacuum that will appreciably increase the amount of steam or vapor that will rise from the hot blow-off water delivered to the separator. The first and second condensing elements are preferably in the form of water sprays, of which the first is supplied by the water of circulation returning from the piping of the boiler washing system, while the second is supplied from a suitable fresh water source and its element of control consists of a thermostat located in the bottom of the condensing chamber wherein the volatiles accumulate when in excess of the capacity of the first condensing element. 55

45 Further features of the present invention relate to details in the construction and arrangement of the apparatus whereby the object of the invention as above outlined may be more fully realized. 60

50 The invention will be fully understood upon reference to the accompanying drawings, in which—

55 Figure 1 is a schematic view illustrating a boiler washing system in which the several features of the present invention are embodied. 75

60 Figures 2 and 3 are, respectively, a top plan view and a side elevation of the apparatus immediately concerned with the condensing unit of the system, and a portion 70 of the filling tank associated therewith. 80

65 Fig. 3^a is an elevation of the auxiliary condenser. 85

70 Figure 4 is a vertical sectional view of the condenser shown in Figures 2 and 3; and 90

75 Figures 5 and 6 are, respectively, a top plan view and a vertical section of the filling tank having combined therewith a modified construction of condenser; the latter being shown partly in vertical section in Fig. 6. 95

80 Referring to Figure 1, A, B, and C are, respectively, the blowoff line, the washout line, and the filling line of a boiler washing system, which lines are usually of such 100 length as to be adapted to supply the drop-pipe connections, such as A¹, B¹, and C¹, at each of a number of stations conveniently arranged for coupling up with a locomotive boiler. Pipe A leads to a separator D, which is adapted to subdivide blowoff water delivered thereto into steam or vapor, which it delivers from its upper end through a pipe D¹ to a condenser E; washout water which it delivers through an overflow pipe D² leading from an intermediate level of the separator to the washout tank F; and sludge or precipitate which it de-

livers through a pipe D³ leading from its bottom to a sewer.

Washout pipe B communicates with a pump G which takes water through the pipe G¹ from the washout tank F and supplies it to said pipe B under pressure, the usual pump governor (not shown) being preferably employed to insure a constant head, and any suitable form of thermostatic valve G² being also provided to temper the washout water delivered by the pump. Washout line B may be connected by a return pipe or circulating line b with the tank F in the manner and for the purpose well known 15 in systems of this kind.

Filling line or pipe C leads from the pump H, which takes water through pipe H¹ from the filling tank I and delivers it to said pipe C under a constant head, the usual pump governor (not shown) for controlling the supply of steam, and therefore the delivery of the pump, being preferably employed. A return or circulating line c from the filling line C maintains circulation 20 and keeps up temperature in the latter. According to one feature of the invention, and as hereinafter described, the water flowing through said circulating line or pipe c, on being returned, is used for condensing exhaust steam, preferably by delivering it to auxiliary condenser E⁵ where it meets exhaust steam from the pumping engines or other steam actuated elements of the system, thereby preventing waste and having its 25 temperature restored before it reaches the filling tank for re-use.

When a locomotive is connected, as by a hose or other flexible connection, with the drop-pipe A¹ of the blowoff line and its contained water and steam are delivered, under the head of pressure in the boiler, through the pipe A to the separator D, the water entering the separator accumulates until it overflows through the pipe D² and enters the 40 washout tank F; the sludge, precipitate, or refuse settles on the bottom of the separator; and the steam or vapor rises to the upper portion thereof, and is conducted toward the filling tank by the pipe D¹. According to the present invention, this steam or vapor does not pass directly to the filling tank but passes to a spray condenser E where it is 45 condensed, raising the temperature of the spray water, and passing as water of condensation along with the spray water to the filling tank. By such condensation a reduction of pressure is induced over the surface of the water in the separator and the evaporation therefrom greatly increased. A suitable 50 condensing apparatus for this purpose may consist of a condensing chamber E having a spray nozzle E¹ supplied by branch P' of cold water pipe P and a delivery pipe E² communicating with the filling tank I. Said pipe E² dips into tank I a distance

sufficient to keep its lower end sealed, so that as condensation takes place in the chamber E, a subpressure or partial vacuum will be developed in the discharge pipe D¹ from the separator D, and the water of the spray together with water of condensation will pass into the filling tank. One important advantage realized from this arrangement resides in the material increase in the number of heat units transferred from the blown-off water to the water of the filling tank, and consequent economizing in the expense of keeping up the temperature of the filling water.

In order that the time during which condenser water is delivered through spray-nozzle E¹ may be automatically regulated to correspond to the flow of steam or vapor from the separator, the lower portion of the condenser chamber E is provided with a thermostat bulb E³, and this is made to control a valve E⁴ located in the branch P' of the water supply pipe P and adapted to be set so that whenever steam is present in the condensing chamber E, the heat therefrom, acting through the thermostat bulb E³, will open the valve E⁴ and deliver water to the spray-nozzle E¹.

Inasmuch as there is normally a small quantity of steam exhausting from the apparatus forming part of the system, for instance, the pumping engine or engines when they are merely keeping up circulation in the filling line or washout line, or both, and it is desirable to save the water therefrom as well as the heat units stored therein, but without putting into operation the main condensing spray, the return flow water of one or both of the lines is utilized for condensing such exhaust steam. This may be accomplished by discharging such return flow in the form of an auxiliary spray, and in the presence of such exhaust steam, and then passing the resultant water to the filling tank. According to one method of realizing this, an auxiliary condenser is provided in the form of an elongated spraying chamber E⁵, which receives exhaust steam from the pumps through the exhaust pipe K and discharges through pipe E⁷ into filling tank I. Auxiliary condenser E⁵ communicates through extension K² with the cross-over pipe D¹ and thereby provides an escape to the main condenser for an excess of exhaust steam; also subjects the engine exhaust to vacuum. The return-flow filling water from pipe c is delivered to the auxiliary condenser through a spray-nozzle E⁶. The capacity of the auxiliary condenser will ordinarily be sufficient to precipitate exhaust steam from one or both of the pumps G and H when they are merely maintaining circulation in the pipes B and C. But if when one or more locomotives are being washed out or refilled, one or both of said pumps is au-

tomatically accelerated to maintain the supply of water in the feed line B or C, the exhaust steam from the pump should be increased to a volume beyond the capacity of 5 the auxiliary condenser, the steam passes beyond its auxiliary condenser into the main condenser and acts thermosatically upon valve E⁴. Similarly, when locomotives are blowing off, and steam and vapor flow 10 through cross-over pipe D¹, the main condenser E will be automatically called into action by the heating effect of the steam upon the thermostat E³.

Exhaust pipe K while shown leading from 15 pumps G and H, which form parts of the system, may be regarded as typical of a supply of waste steam from any apparatus.

The feature of a normally acting reduced capacity condensation device coupled with 20 an automatically introduced condenser of abnormal capacity is not limited, in its application, to the use of separate condensing chambers, or a large and a small condensing space. On the contrary, as shown in Figures 25 5 and 6, spraying water from the return or circulating pipe c may be delivered into the same chamber as the spray of larger capacity; for instance, the chamber provided by a large diameter pipe E^x which receives 30 an extension D^{1x} from the pipe D¹ leading from the separator D, and also receives its main or large capacity spray from the pipe E¹ automatically controlled by the thermostatic valve E⁴. In order to subject the 35 valve E⁴ to the heat conditions in the condenser E^x, the horizontal extension E^y of the condenser receives the thermostat bulb E³ which controls the valve E⁴. Circulating injector E^w, at the elbow between the chamber E^x and the extension E^y, induces a flow 40 of water from tank I into the extension E^y, and this, mixing with the steam and vapor therein, increases the condensation effect 45 therein. If, at any time, the volume of steam arriving through pipes D¹, D^{1x}, is greater than can be condensed by the spray of the circulating pipe c, the thermal effect upon the thermostat bulb E³ will immediately 50 release water from the valve E⁴ and increase the volume of the spray, with the result that complete condensation will be effected. Condensation occurring in chamber E^x, as in chamber E, develops sub-pressure 55 sure in the cross-over pipe D¹ from the separator, and thereby raises evaporation in the separator.

It is not the purpose to limit the scope 60 of this invention to a boiler washing system having a condenser of dual capacity normally operating under its reduced or auxiliary capacity, but automatically changing to its main or full capacity under the influence of an increased volume of steam or 65 vapor. On the contrary in the embodiment

shown in Figures 1 to 4 no less than in that disclosed by Figures 5 and 6, the condensing apparatus is to be regarded as a unitary arrangement of two condensing elements coordinated and operating in this particular 70 way. This constitutes an important feature of the present invention. Were it not for the use of the auxiliary spray, valve E⁴, so long as the steam entering the condenser remained small, would be opening and closing constantly at short intervals by the alternate accumulation of steam and the condensation thereof. But with the auxiliary condensing medium the small volume of 75 steam delivered is constantly cared for by the condition of a constant discharge from the circulating pipe, and the main condenser is left normally out of action until, but ready for instant action when, an abnormal quantity of steam arrives, and promptly retires from action as soon as the excessive volume of steam has been condensed.

A drainage pipe E^s connects the bottom of the condenser chamber E with the tank I, and so keeps the water in the chamber E below the thermostat bulb E³, and leaves the latter exposed to the action of the steam entering the chamber. But as long as the main spray E¹ is acting, chamber E will fill to the overflow pipe E² and keep the pipe E^s sealed, thereby maintaining in chamber E vacuum necessary to increase evaporation in separator D.

Some of the important advantages arising from the use of two independently acting condensing elements of relatively large and small capacity, operating under conditions and arranged as herein described, are that condensing action, and water consumption incident thereto may be largely regulated in time and quantity according to the demand for condensation; each condenser can be made to operate under the particular normal conditions for which it is intended; and in case of an overload of the small condenser, set for normal action of low capacity, the main condenser will be automatically called into effect. For example, on the one hand we have the small, auxiliary condenser 100 as a constantly acting condenser that uses water of circulation returning to the tank and keeps up the temperature thereof by the use of steam exhausted from the pumping engines, and therefore operates without 105 additional expense for either water or steam. It can be adjusted for normal maximum capacity of action because when the pumps are more active, as when meeting heavy washout and filling water consumption at 110 the drops, the surplus exhaust of steam can flow over into the main condenser and, by its temperature, call into action the main condensing spray. On the other hand, we have the main condenser normally inactive, 115 120 125 130

but automatically responsive to a blow off, and also to the aforesaid surplus of steam in the auxiliary condenser.

I claim:

5. 1. In a boiler washing system, a storage tank, a line of communication adapted to receive steam and vapor and deliver the same to said storage tank, and a condenser interposed in said line of communication; said 60 condenser comprising means for delivering sprays of relatively small and large capacity; a valve for controlling the means for delivering the large spray and a thermostatic governor for said valve which is subject to temperature effect of steam or vapor accumulating in the region in which the spray of large capacity acts.
- 10 2. In a boiler washing system, a line of communication adapted to receive and deliver 70 blow-off products from a boiler, condensing apparatus having connections through which it receives volatiles delivered by said line of communication, said condensing apparatus including a first condensing element which 75 is of minor capacity and a second condensing element which is normally inactive and of major capacity, and thermostatic means controlling the second condensing element; said thermostatic means being located within the 80 condenser, at a point that is reached by the volatiles only when in volume in excess of the capacity of the first condensing element.
- 15 3. In a boiler washing system, a line of communication adapted to receive and deliver blow-off products from a boiler, a condenser having connections through which it receives volatiles delivered by said line of communication, said condenser including a first condensing element of a minor capacity 85 and normally active and a second condensing element of major capacity and normally inactive, and a thermostatic element controlling said second condensing element; said thermostatic element being located in the 90 condenser at a point remote from the first condensing element and out of reach of volatiles accumulating in the condenser in a volume within the capacity of said first condensing element.
- 20 4. In a boiler washing system, a container for water of condensation, and a condenser adapted to discharge into said container; said condenser discharging below the water line in said container and having a normally 95 submerged injector inducing mingling of water of the container with the precipitate of the condenser.
- 25

5. In a boiler washing system, a separator, a container for water of condensation, and a spray condenser interposed between said separator and container; said condenser discharging below the water line in said container and having a normally submerged injector inducing mingling of the water of the container with the precipitate of the condenser.

6. In a boiler washing system, a separator, a container for water of condensation, and a condenser interposed between said separator and container; said condenser comprising 75 main and auxiliary spray-jets and a chamber receiving the spray from both said jets and discharging below the water line in said container and having a submerged injector inducing mingling of water of the container 80 with the precipitate of the condenser.

7. In a boiler washing system, a separator, a container for water of condensation, and a condenser interposed between said separator and container; said condenser comprising main and auxiliary spray-jets and a chamber receiving sprays from both said jets and discharging below the water line in said container and having a submerged injector inducing mingling of water of the container 85 with the precipitate of the condenser; said condenser having in its discharge end a thermostat controlling the main spray-jet.

8. In a boiler washing system, a blow-off pipe, a condenser receiving volatiles from 90 said blow-off pipe, said condenser including a normally inactive condensing element supplying condensing water sufficient to condense said volatiles, means in said condenser responsive to the heat of said volatiles, adapted to release water through said condensing element, a water supply pipe adapted to deliver water of condensation provided by said condenser, a steam pump adapted to feed said water supply pipe, a return flow line 100 returning water from said supply pipe, said condenser also including a condensing element of minor capacity supplied with water by said return flow line, and means delivering exhaust steam from the pump into the condenser and in condensing relation to said condensing element of minor capacity; said condenser being constructed to subject an excess volume of exhaust steam to the condensing element first named.

Signed at Chicago, Illinois, this 4th day of September, 1919.

FRANK S. WICHMAN.
